UNITED STATES PATENT OFFICE.

PHILIP C. WENTWORTH, OF PROVIDENCE, RHODE ISLAND.

RING TRAVELER.

1,415,069.

Specification of Letters Patent. Patented May 9, 1922.

Application filed January 11, 1921. Serial No. 436,585.

To all whom it may concern:

Be it known that I, PHILIP C. WENTWORTH, a citizen of the United States, residing at Providence, county of Providence, 5 State of Rhode Island, have invented certain new and useful Improvements in Ring Travelers, of which the following is a specification.

This invention relates to ring travelers for use in ring spinning or twisting and particularly to the construction of such a device in such manner as to avoid or eliminate the loading of the traveler by lint or fly or otherwise.

During the years in which ring spinning and twisting have been developing there have been marked advances and many refinements in the art. The ring traveler itself has formed the subject matter of some improvement, but on the whole has retained its original simplicity. In the production of ring travelers, however, and in their use, refinement as to certain matters have been carried to a considerable degree. The relation of the weight of the traveler and the retardant effects of both weight and air resistance have been known and ring travelers have for a long time been manufactured on the strictest specifications.

One of the specifications most insisted upon has been exactness of weight. Other specifications have had to do with air resistance and others have had to do with wear and serviceability from the operating standpoint.

Throughout all these years of the development of ring spinning and twisting there has been present a well known common fault which by its general nature seems to have been regarded as unavoidable. This fault or difficulty in both spinning and twisting has been the loading of the traveler by such fine particles of fibre or filament as are usually termed fly or lint. The degree of loading of travelers has varied principally with the nature of the yarn being spun or twisted. Short staples have been the principal offenders in this regard, although there is a tendency even with the longer staples for the traveler ultimately to load.

The results of such loading have been well known. The resultant variation from the original carefully specified weight of the travelers have been obvious. In the same way the change in air resistance between the

loaded and unloaded traveler has been easily recognized. The results have been broken end, waste and delay, and a general upsetting of exact calculations to produce perfect spinning or twisting conditions. 60

In spite of the fact that the problem has been generally recognized but little has been attempted to overcome it. Certain so-called cleaners have been produced which have attempted to knock from the traveler its load and thus restore or partially restore it to its original weight. Such method, however, of cleaning or clearing the rapidly moving traveler by physical contact with a stationary body is by its very nature difficult. While such devices have been installed they have in actual practice been used with poor effect, especially as such devices really require fine adjustment for each different size of traveler that might be run on 70 a frame or on a set of frames in any mill. Only a crude adjustment of such devices is possible and under any crude method of adjustment these devices are worthless. 75

My invention contemplates the construction of a traveler which in its operation will avoid this loading and thus maintain the traveler at its desired weight, thus making clearing or cleaning unnecessary as my traveler at all times remains clean. The importance of maintaining the traveler at all times clean and clear without alternating phases of loading and discharging will be obvious to all those skilled in the art and to all others who can appreciate the desired 90 nicety in the construction and adjustment of the elements employed in this kind of work. 85

There are certain other features involved in my invention which are at once incidents 95 of the general embodiments contemplated by my invention and at the same time important features in such travelers are considered as articles of manufacture and as practical operating equipment. These features have to do principally with maximum durability of the horns of the traveler and the greatest possible resiliency in the circles of the travelers in the region in which they are flexed when being sprung over the 105 flanges of the ring. 100

Without attempting to enter further into the general scope of the purposes of my invention, I shall proceed at once to the disclosure of certain characteristic forms and 110

a description and discussion of the same as best illustrating my invention. Throughout the specification and drawings like reference characters are employed to indicate corresponding parts, and in the drawings:

Figs. I, II and III, respectively, are side, end and top views of a traveler in accordance with my invention.

Fig. IV is a diagrammatic view illustrating the position of the traveler on the ring relative to the spindle.

Fig. V a fragmentary view of a ring with traveler positioned thereon as in operation.

Figs. VI and VII are top views showing further modifications of my traveler, and

Fig. VIII is a side view of Fig. VII.

Referring first to Figs. I, II and III as a very satisfactory illustrative embodiment, I have indicated at 1 what may be referred to as the body of a standard type of traveler. The traveler 1 comprises a center or circle portion 2 and a terminal or end portion or horns 3. In practice I provide an opening 4 cut through the traveler in the region of its circle portion or according to the English terminology, its bow.

The result of this simple vent or opening 4 is peculiar. It is of course a matter of greatest difficulty to give exact theories for the performance of any part traveling at the high speed at which a traveler operates. Without therefore committing myself to an exact theory, but in order to disclose for the benefit of others my own conclusions for whatever benefit they may involve, I will endeavor to explain what seems to be the operation of such a traveler.

Referring to Fig. IV it will be seen that I have indicated diagrammatically at R a plan view of the ring, and at S the spindle to which passes the thread Y. I have indicated at 1 the traveler on the ring R. Those familiar with the performance of the traveler in spinning and twisting need only be reminded that the loading of the traveler almost universally appears on that portion of the circle or bow adjacent to the outer upper edge of the upper ring flange. As is well known, the traveler while theoretically floating free on the ring necessarily makes more or less continuous contact between its inner horn and the lower inner face of the upper flange of the ring. Furthermore, as is indicated in Fig. V, the traveler as it is led by the yarn Y has a tendency to tip forward due to the lifting action of the thread on its rear edge. These movements are but slight and while very difficult to prove positively with the traveler at speed, nevertheless I believe are generally accepted and at least I find them sufficiently supported in practice to constitute acceptable theories.

The tipping action of the traveler 1 on the ring R brings the upper surface of its circle or bow portion 2 more or less against the

resistance of the air. This exposes the slot or vent 4 to the action of the air and admits what constitutes a draft directly into the traveler itself and transversely or substantially transversely to the circle or bow over which the fibres of the load tend to drape themselves in their normal accumulating effect. At this point it will be noted that there is reasonable ground to suppose that the lint or fly on the surface of the yarn is more or less scraped off or tends to be scraped off by the edge of the circle of the traveler under which it passes. Such fly once detached is subjected to several influences which according to my theory may be analyzed as follows: first, the tendency of the rapidly moving yarn to comb the fly through the traveler; second, the centrifugal tendency of the traveler and all things moving with it; third, the backward air draft due to the rush of the traveler through the air. The components might very reasonably produce a resultant motion of the fibre to fold over the traveler with free ends trailing behind and move outward on the traveler until reaching the position in which they are usually found, i. e. on the outer portion on the circle or bow. However much truth or error there may be in my analysis or theory, the fact remains that I have been able to counteract and overcome this loading tendency and to cause travelers to operate even on short staple cottons without any loading whatsoever.

The slot 4 illustrated in the traveler of Figs. I to III inclusive of the drawing apparently admits or directs a strong draft to the intermediate portion of any fibre which may find lodgment on the traveler. I believe that this draft striking the fibre at this place clears the overfolded end and permits the fibre to be blown back and thus clear the traveler.

I have above referred to my invention as preventative and it may be that with this draft directed through the traveler that a large portion of the potential load is prevented from finding any lodgment on the traveler at all, but passes off in the train on the revolving traveler.

The draft through the slot 4 furthermore tends to cool the traveler and particularly to keep the inner or contacting horn cooled and prevent it from heating by continued contact with the ring as sometimes happens.

Further referring to Figs. I to III inclusive, it will be noted that the circle or bow of the traveler thus provided with a central slot or opening is of considerably decreased metallic body. This produces a peculiar and distinct advantage in the potential physical structure of the traveler as a manufactured article.

The travelers are manufactured from steel wire or steel tape being cut and formed

rapidly by automatic machines. Such travelers have however to be finished and particularly to be tempered. The wear on the inner horn of the traveler ultimately destroys its usefulness and in fact as soon as wear begins to develop on the inner horn a corresponding wear is developed on the adjacent contacted surface of the ring so that the less the traveler is reversed or changed the greater is the accumulative wearing result.

This necessitates a very hard temper for the traveler in order that the horns may give proper wear but this hard temper desired at the horns makes the rings brittle and they are frequently broken when sprung over the flanges of the ring in putting them on. My new traveler with its diminution of metal in the arch of the circle relieves this difficulty in two ways: first, by physically decreasing the amount of metal at this part and so making the traveler more flexible, and second, by reason of its increased radiating surface the opened up arch of the circle radiates the heat applied so that it actually takes on a lower temper and is less liable to break.

The above principles apply to such modifications as are shown in Figs. VI and VII. In Fig. VI there is substituted for the slot 4 a series of holes 5 which have a similar function and result. In Fig. VII I have shown a form in which I provide a double slot 6, 6 having an intermediate bar 7 which is preferably slightly depressed. Such modifications are shown as merely suggestive changes over the structure shown in Figs. I, II and III, but obviously a wide range of draft producing apertures, surfaces or flanges might be made giving the same or similar results to those described herein. As simplicity is so highly desirable and the advantages of applicant's preferred form are so many, this simple vented form is utilized herein as illustrative of the principles of my invention within which all other modifications must be understood as

included if within the limits of the appended claims.

What I therefore claim and desire to secure by Letters Patent is:

1. A ring traveler comprising a circle portion and terminal horns and having an opening through said circle portion.
2. A ring traveler comprising a circle portion and terminal horns and having a slot through said circle portion.
3. A ring traveler having an opening through its body portion.
4. A ring traveler and a draft producer carried thereby.
5. A ring traveler and a draft producer carried by the traveler between the horns thereof.
6. A ring traveler comprising a bow portion and terminal horns, and a draft producer between said horns.
7. In combination with a spinning ring, a ring traveler and a draft producer mounted on said ring.
8. A ring traveler comprising a bow portion and terminal horns, and means disposed between said horns to prevent the accumulation of lint on the traveler bow.
9. In a spinning unit, a ring traveler constructed and disposed to create a current of air across the traveler during its circuit of the ring.
10. A ring traveler, and means carried thereby to prevent accumulation of lint thereon.

11. A ring traveler comprising a bow and horns, said traveler being formed to discharge lint disengaged from the thread.

12. A ring traveler having a lint clearing area for discharging lint lodging thereon.

In testimony whereof I affix my signature in presence of two witnesses.

PHILIP C. WENTWORTH.
